further expand. The concussion or peak pressures are silenced by the excess pressure being exerted and dissipated or cushioned by compression of air and/or gases residual in chambers 22.

The normal pressure residual therein is atmospheric or slightly above same, so that since the exhaust pipe 11 has atmosphere pressure or slightly above the same therein, the cushioned gas freely flows from the muffler to and through the tail pipe until the pressures rise in the discharge system. However, in so doing there is always present the cushioning action and relatively free discharge to the tail pipe so the exhaust is substantially silent, all without the customary back pressure creation and resulting decrease in engine efficiency.

While the invention has been illustrated and described in great detail in the drawings and foregoing description, the same is to be considered as illustrative and not restrictive in character.

The several modifications described herein, as well as others which will readily suggest themselves to persons skilled in this art, all are considered to be within the broad scope of the invention, reference being had to the appended claims.

The invention claimed is:

1. A muffler having an elongated body with a plurality of chambers substantially coextensive therewith and closed ends with substantially equal area inlet and discharge means, the chambers freely communicating one with the other at the discharge ends and certain of the chambers freely communicating with the inlet means at the inlet end, the remainder of said chambers at the inlet end being sealed from the inlet means to form cushioning means, the two groups of chambers having restricted communication near the discharge ends thereof, each group of chambers including a pair thereof, the chambers of each such pair being separated by a chamber of the other pair.

2. A muffler having an elongated body with a plurality of chambers substantially coextensive

therewith and closed ends with substantially equal area inlet and discharge means, the chambers freely communicating one with the other at the discharge ends and certain of the chambers freely communicating with the inlet means at the inlet end, the remainder of said chambers at the inlet end being sealed from the inlet means to form cushioning means, the two groups of chambers having restricted communication near the discharge ends thereof, and the several chambers in the body being formed by substantially X-arranged partitions, each partition being common to a pair of adjacent chambers.

3. A muffler including an elongated, elliptical sectioned body with intake and exhaust at opposite ends, X-arranged partitions therein substantially coextensive with the major length thereof, and baffle and diversion means at the inlet end closing two opposite resulting chambers at that end and diverting inlet gases to the other chambers and dividing the gases substantially equally therebetween.

4. A muffler as defined by claim 3 wherein all chambers have restricted communication at the discharge end thereof and for an appreciable length of said chambers but less than half the length of the same.

5. A muffler as defined by claim 3 wherein all chambers at the discharge end have free communication with the muffler exhaust.
